(57) **CLAIM**

I claim the ornamental design for a vehicle window hawk sign, as shown and described.

DESCRIPTION

FIG. 1: is the front view of the vehicle window hawk sign; FIG. 2: is the front perspective view of the vehicle window hawk sign;

FIG. 3: is the front internal perspective view of the vehicle window hawk sign; and,

FIG. 4: is the perspective rear view of the vehicle window hawk sign.

The broken line in FIG. 3 is for illustrating portions of the vehicle window hawk sign that form no part of the claimed design.
